UNITED STATES PATENT OFFICE.

LEO BLUHM, OF NEW YORK, N. Y., ASSIGNOR TO PHOENIX MANUFACTURING CO. INC.,
OF NEW YORK, N. Y., A CORPORATION OF NEW YORK.

DESIGN FOR A PRINTED FABRIC.

Application filed July 5, 1923. Serial No. 6,680. Term of patent 3½ years.

To all whom it may concern:

Be it known that I, LEO BLUHM, a citizen of the United States, and a resident of the city of New York, borough of Manhattan, in the county and State of New York, have invented a new, original, and ornamental Design for a Printed Fabric, of which the following is a specification, reference being had to the accompanying drawing, forming a part thereof, wherein the essential features of the design comprise a broken plaid,

the boundary bands of which are made up of mottled shading to produce a chenillelike effect disposed upon a ground of contrasting color.

The drawing represents a plan view of a piece of fabric embodying my design.

What I claim and desire to secure by Letters Patent is:

The ornamental design for a printed fabric substantially as shown and described.

LEO BLUHM.
